CLAIM

The ornamental design for an egg holder for use with a stand for decorating eggs, as shown and described.

DESCRIPTION

FIG. 1 is a front bottom perspective view of an egg holder for use with a stand for decorating eggs showing my new design;

FIG. 2 is a front elevational view thereof;

FIG. 3 is a top plan view thereof; and,

FIG. 4 is a bottom plan view thereof.
